(57) **CLAIM**

The ornamental design for a hand tightened hydraulic fitting, as shown and described.

DESCRIPTION

FIG. 1 is a front perspective view of a first embodiment of a hand tightened hydraulic fitting.

FIG. 2 is a rear perspective view of the first embodiment of a hand tightened hydraulic fitting.

FIG. 3 is a front elevation view of the first embodiment of a hand tightened hydraulic fitting.

FIG. 4 is a rear elevation view of the first embodiment of a hand tightened hydraulic fitting.

FIG. 5 is a top plan view of the first embodiment of a hand tightened hydraulic fitting.

FIG. 6 is a bottom plan view of the first embodiment of a hand tightened hydraulic fitting.

FIG. 7 is a left side elevation view of the first embodiment of a hand tightened hydraulic fitting.

FIG. 8 is a right side elevation view of the first embodiment of a hand tightened hydraulic fitting.

FIG. 9 is a cross-sectional view of the first embodiment of a hand tightened hydraulic fitting taken at line 9-9 in FIG. 3.

FIG. 10 is a front perspective view a second embodiment of a hand tightened hydraulic fitting.

FIG. 11 is a rear perspective view of the second embodiment of a hand tightened hydraulic fitting.

FIG. 12 is a front elevation view of the second embodiment of a hand tightened hydraulic fitting.

FIG. 13 is a rear elevation view of the second embodiment of a hand tightened hydraulic fitting.

FIG. 14 is a top plan view of the second embodiment of a hand tightened hydraulic fitting.

FIG. 15 is a bottom plan view of the second embodiment of a hand tightened hydraulic fitting.

FIG. 16 is a left side elevation view of the second embodiment of a hand tightened hydraulic fitting.

FIG. 17 is a right side elevation view of the second embodiment of a hand tightened hydraulic fitting; and,

FIG. 18 is a cross-sectional view of the second embodiment of a hand tightened hydraulic fitting at line 18-18 in FIG. 12. Broken lines illustrate the environment in which the hand tightened hydraulic fitting is used and form no part of the claimed design.
